C. C. Allen
ATTORNEYS.

UNITED STATES PATENT OFFICE.

JOHN H. LAIRD, OF LOUISVILLE, KENTUCKY.

AUTOMOBILE HEADLIGHT.

Application filed January 4, 1923. Serial No. 610,635.

To all whom it may concern:

Be it known that I, JOHN H. LAIRD, a citizen of the United States, and residing at Louisville, county of Jefferson, and State 5 of Kentucky, have invented certain new and useful Improvements in Automobile Headlights, of which the following is a specification.

My invention relates to motor vehicle 10 lamps in which the upward rays, which would be blinding to approaching persons, are eliminated, and in addition certain advantageous direction is given to certain rays to light the ground near the front and to 15 the sides of the motor vehicle.

It is my object to provide as perfect as possible a device of the noted character and at the same time to eliminate to the greatest possible extent any variation over present 20 practice in forming reflectors, installing and adjusting light bulbs etc.

It is more specifically my object to provide a small piece of properly formed reflective material, which is to be attached at 25 the apex of the lamp reflector, this piece not only interrupting rays that tend to diverge upwardly from the reflector, but also reflecting said rays back to the reflector at a proper angle, and cutting out all tendency 30 to upward deflection of these rays or other rays directed backwardly.

As is well known the ordinary parabolic reflector, with a properly located light bulb, would throw a perfectly parallel beam of 35 light, in a direction of the axis of the reflector, if the light filament could be reduced to a point. However, since this is not feasible, and since certain rays of light emanating directly from the lamp are not 40 confined by the reflector, the present day automobile lamps require some kind of a special lens in order to be effective, within legal limits of beam direction.

I am familiar with various types of specially-shaped reflectors to replace the normal parabolic reflectors, but these are too costly to make a good manufacturing proposition.

I am aware that others have tried to attach onto the lamp bulbs themselves small 50 reflective mirrors, but the defect of doing this is that the lamps are not of uniform size, and are not spherical at the end, and also that such reflectors do not truly avoid the incorrect deflection of rays of light.

I accomplish my object above set forth by

that certain construction and arrangement of parts to be hereinafter more specifically pointed out and claimed.

In the drawings:

Figure 1 is a perspective view taken looking into a reflector equipped with my novel device. 60

Figure 2 is a central cross section taken vertically through a reflector, in the position in which it is to be installed in a lamp. 65

Figure 3 is a top plan view of the attachment device.

It will be noted that the reflector 1 is an ordinary parabolic reflector of the type used in practically all present day automobile lamps. The method of mounting the reflector in the lamp casing, is not of importance to my invention and hence is not shown or described. 70

I secure the lamp bulb 2 in the reflector in 75 the usual manner, through a hole at the apex thereof, so that the lamp filament lies in the axis of the reflector.

In addition to the reflector my invention includes a special stamping or the like of 80 metal, which is burnished, or silvered in some manner to have reflective surfaces.

This stamping has a more or less annular strip 3, terminating at the front in a spherical shaped piece 4. This piece 4 must be 85 far enough away from the reflector apex to permit the lamp to be set between it and the reflector and extends from the horizontal ring portion 3 upwardly only. It is also limited in area so that it is less than 90 a quarter of a spherical surface, the inside line of this piece being so set that it does not interrupt any rays from the lamp which would otherwise strike the reflector at some point. It is arranged to interrupt all rays 95 from the light bulb filament, indicated at 5, which would otherwise emerge from the lamp at a slant above the horizontal, and would not strike the reflector. It does not eliminate any rays which would emerge 100 directly from the lamp at a downward slant.

Since the surface of this spherical segment is reflective at its inner or concave side, it will deflect directly back to the reflector, any rays that strike it from the filament. 105 It is also arranged so that the spherical center is at the center of the filament of the bulb when properly adjusted in place, as shown in dotted lines in Figure 2.

At the rear of the ring like plate another 110

reflector 6 is formed, which is spherical or approximately so and faces forwardly of the lamp with its reflective surface. This reflector is so arranged that the rays emanating therefrom are directed downwardly of the horizontal.

As will be noted this rear reflector is also located above the horizontal line formed by the ring shaped support, and both reflectors 10 are integral with the ring, and turned up and formed therefrom, as a stamping.

The rear reflector is cut away to clear the central hole in the back of the reflector as indicated at 7, and is formed with rivet holes 8, by means of which it is riveted to the rear of the reflector. In mounting the device the hole formed in the rear reflector is set to register with the hole in the main reflector and the said rear reflector of the 20 insert is then riveted in place, or held in any other desired permanent manner.

The outer reflector 4 of the insert is so arranged that its focus is the same point as the focus of the parabolic reflector in which it is mounted, both of the said reflectors 25 having a common focus at the center of the light filament.

Dotted lines have been drawn in Figure 2 to indicate the direction of light rays from the filament in my device when the light bulb is properly adjusted with its filament at the con-focal point of the main reflector and the reflector 4.

Light rays emanating directly are stopped by the spherical reflector 4 acting as an opaque body. They are then directed back through the filament to the main reflector and thus strike it correctly to be deflected again into the truly horizontal beam from 40 the main reflector. Such light rays as would tend to strike the main reflector from the filament and be deflected upwardly near the apex of the reflector, due to the fact that the filament is not a mere point of light, will be caught by the rear reflector 6 and deflected back through the filament point, and thence downwardly out of the reflector to the ground directly in front of the lamp. This same deflection will take place as to 50 rays which are incorrectly sent back by the reflector 4, due to the dimension of the filament. The chief reason for the rear reflector 6 is to prevent the deflection which would occur if it were omitted. Rays coming in a horizontal path against the reflector 4 from the main reflector would be deflected thereby to the lower half of the main reflector and thence upwardly in the very angle that is to be avoided.

60 It will thus be noted that by my insert I take care of the full contingency of incorrectly escaping beams of light, and also that I do not reduce the number of beams of light which would emerge from the lamp,

if same was not unobstructed. I am not advised of any other device which accomplishes this without the formation of an expensive special reflector, and I wish to avoid any devices which form part of the bulbs themselves, since such devices vary with the bulbs, and cannot be truly supported in the correct con-focal position with the main reflector, since with every adjustment of the bulbs to get them at the focal point of the parabolic reflectors, the relative position of the attached spherical reflector elements if any, are changed with relation to the parabolic reflector. By the use of the term parabolic in the claims that follow, I desire to cover that range of reflectors which have the general functions of true parabolas, and not to be confined to true and undistorted parabolas. Thus reflectors having partially a true parabolic shape and partially distorted, or having flutings to cut out 85 filament images, or partially on catenary curves, are generally classed by me as parabolic reflectors.

Having thus described my invention, what I claim as new and desire to secure by Letters Patent is:

1. In a lamp, a reflector of parabolic shape, and a device fixedly secured to the reflector so as to be located at its apex, and shaped to clear a light bulb, said device including a support and a spherical reflector having a con-focal relation with the parabolic reflector, and set in the reflector and proportioned so as to obstruct by its opacity, direct rays of light emanating from the bulb that would otherwise pass out through the upper half of the lamp, but otherwise to avoid obstruction of light emanating from said bulb, and also including another concave reflector located to the rear of the spherical reflector entirely above the horizontal axis of the reflector and interspaced from the spherical reflector, to prevent reflected rays from the parabolic reflector from striking the spherical reflector at an angle that would ultimately result in an upward emanation from the lamp, but intercepting no other rays.

2. An insert to be fixedly attached to parabolic reflectors comprising a support, in the form of a hollow ring like body, a spherical reflector of less than a quarter of a sphere formed at the forward end of said support, and a concave reflector formed at the rear end of said support, said two reflectors both located to one side of said support, and said support being in a single plane and all reflectors having a focus at a common point.

3. An insert to be fixedly attached to parabolic reflectors comprising a support, in the form of a hollow ring like body, a spherical reflector of less than a quarter of

a sphere formed at the forward end of said support, and a concave reflector formed at the rear end of said support, said two reflectors both located to one side of said support, and said support being in a single plane, the reflectors and support being formed in one piece and both reflectors having a focus at a common point.

4. In combination with a main parabolic reflector, and a light at its inner focus, a mirror element adapted to obstruct and deflect direct rays from the light that would pass out of the reflector at an upward slant, and a separate element adapted to shield that portion of the main reflector that would otherwise reflect rays of light to the mirror element at such an angle as to ultimately escape from the lamp at an upward slant.

5. In combination with a main parabolic reflector, and a light at its inner focus, a mirror element adapted to obstruct and deflect direct rays from the light that would pass out of the reflector at an upward slant, and a separate element adapted to shield that portion of the main reflector that would otherwise reflect rays of light to the mirror element at such an angle as to ultimately escape from the lamp at an upward slant, said separate element also formed as a mir-

ror adapted to deflect rays from the light 30 forwardly and downwardly.

6. An insert to be fixedly attached to parabolic reflectors comprising a support, in the form of a hollow ring-like body, a shield covering in area around a half circle and 35 mounted at the forward end of the ring-like body, said ring-like body adapted to clear a lamp bulb set with its filament in the plane of said ring-like body, and the shield adapted to block only such rays as emanate from 40 the light filament in an upward slant in a direction to escape contact with the parabolic reflector to which the insert is attached.

7. An insert to be fixedly attached to parabolic reflectors comprising a support, in 45 the form of a flat ring-like body having a portion integral therewith and turned up to form a shield covering in area around a half circle and mounted at the forward end of the ring-like body, said ring-like body 50 adapted to clear a lamp bulb set with its filament in the plane of said ring-like body, and the shield adapted to block only such rays as emanate from the light filament in an upward slant in a direction to escape contact with the parabolic reflector to which the 55 insert is attached.

JOHN H. LAIRD.
